UNITED STATES PATENT OFFICE.

DEXTER W. ALLIS, OF REVERE, MASSACHUSETTS, ASSIGNOR, BY MESNE ASSIGNMENTS, TO BOSTON TALKING MACHINE COMPANY, OF BOSTON, MASSACHUSETTS, A CORPORATION OF MAINE.

ACOUSTIC APPARATUS FOR DETECTING SOUND-VIBRATIONS IN NON-GASEOUS MEDIA.

1,149,610.

Specification of Letters Patent.

Patented Aug. 10, 1915.

Continuation of application Serial No. 420,510, filed March 11, 1908. This application filed May 15, 1909, Serial No. 496,161. Renewed January 22, 1910. Serial No. 539,602.

To all whom it may concern:

Be it known that I, DEXTER W. ALLIS, a citizen of the United States, residing at Revere, in the county of Essex and State of Massachusetts, have invented an Improvement in Acoustic Apparatus for Detecting Sound-Vibrations in Non-Gaseous Media, of which the following description, in connection with the accompanying drawings, is a specification, like letters on the drawings representing like parts.

My invention relates to acoustic apparatus for detecting sound vibrations in non-gaseous media, as distinct from gaseously transmitted sounds, such, for example, as articulate speech, being more particularly concerned with the provision of an apparatus for selecting sound vibrations from non-gaseous media only, and microphonically converting such vibrations, through an agency insulated from all other vibrations, into an undulatory electrical current adapted to act upon a suitable listening device, such, for example, as an ordinary telephone receiver. In the present embodiment of my invention this object is attained by providing an apparatus having a contact member such as will remain unresponsive to gaseously transmitted sound vibrations. Such member may be held in contact with a solid or liquid body through which sound vibrations are conducted, and serve to transmit the sound vibrations through the walls of the contact member to an associated microphone of any ordinary construction, which latter is appropriately insulated against all sound vibrations except those received through the contact member by reason of its contact with the vibrating solid or liquid body. The disturbance thus caused in the insulated microphone may be utilized to vary the resistance of an electric current and thereby to create electric undulations corresponding to the sound vibrations in the solid contact member, such electric undulations being transmitted to a telephone receiver by suitable conductors passing through the sound insulated inclosure of the microphone.

Such invention may have useful application for many different purposes, such, for example, as the detection of leaks in liquid conducting pipes, the investigation of broken bearings in shafts or axles, or the accuracy

in general of the movement of revolving bodies, the location of broken or improperly moving parts in machines where trouble of this kind is experienced and cannot be located, and for any other purpose where the detection is desired of sound vibrations in a solid or liquid body to the exclusion of all voice-caused or other sound vibrations transmitted through the surrounding atmosphere or other gaseous medium.

The invention will be best understood by reference to the following description when taken in connection with the accompanying illustration of one specific embodiment thereof, while its scope will be more particularly pointed out in the appended claims.

In the drawings: Figure 1 shows a form of portable apparatus embodying one form of my invention; Fig. 2 is a central, vertical section on the line 2—2 in Fig. 1; and Fig. 3 is a similar section on the line 3—3 in Fig. 2.

While the apparatus which forms the subject matter of my invention may be constructed in various ways and may be either portable or non-portable according to the purpose to which it is applied, in the form which for illustrative purposes is shown in Fig. 1 it consists of a portable device having the handle 1, the latter connected by the stem 2 to a contact member 3. The latter may be of any desired shape, presenting contact walls of any desired area, and may be of any suitable material properly to respond by contact to the sound vibrations of solid or liquid bodies, while being non-responsive to the sound vibrations of the surrounding atmosphere or other gaseous media. Herein, however, it is preferably of metal, such as iron or brass, and is rounded as shown to permit its ready application by contact to the bearing of a shaft or to any other object or body, the sound vibrations of which are to be detected.

For the purpose of insulating the microphone, the contact member herein is constructed in the form of a casing or inclosure. This consists of the main body portion 4, which has its open end hermetically sealed by means of a plate 5 soldered to the casing and provided with a threaded stud 6, which is engaged by the nut 7, the latter serving to hold in position the outer closure 8. The walls of the closure are purposely

formed of a sufficient thickness and mass so that it is incapable of vibrating as a diaphragm or otherwise in response to any ordinary air vibrations or other vibrations 5 transmitted through the gaseous medium in which the casing is placed. When placed in contact with a solid or liquid body, however, sound vibrations may be readily communicated therefrom to the solid and relatively 10 thick walls of the casing and the latter will act as a transmitter to cause a disturbance in the microphone inclosed within the same.

The microphone may be of any desired 15 construction so long as it is acoustically associated with the solid contact member, my invention broadly considered having no particular reference to the detail construction of the microphone itself. In the particular 20 form shown in the drawings a common form of microphone button is illustrated rigidly and mechanically attached to the inner walls of the contact member by means of the threaded shank 9. The latter supports 25 the fixed carbon contact or electrode 10 for the microphone, there being provided a mica diaphragm 11 held against the outer face of the carbon electrode by means of a washer 12 and nut 13. The mica disk supports 30 the thin cup-shaped casing 14 for the button, to the inner end wall of which is secured the movable carbon electrode 15, the space between the two electrodes being filled or partially filled with carbon granules 16, 35 which, together with the electrode, are held in place by the surrounding annular ring 17 of cotton or other suitable material. It is not necessary that the microphone should be surrounded wholly by the walls of the contact 40 member so long as it is suitably insulated against gaseously transmitted sound vibrations and so long as the contact member, whatever may be its shape or exposed area, is capable of transmitting its contact- 45 received vibrations to the microphone.

For the microphone there are provided suitable connections to an appropriate listening device. While the microphone may be electrically insulated from the casing, if 50 desired, herein the electrode 10, being attached to the casing, is electrically connected thereto and the casing is included in one side of the circuit. The other electrode 15 is connected to the microphone casing 14 and 55 the latter to the conductor 18, which is embedded in an insulating tube 19 fitting tightly within the connecting stem 2. The conductor passes through the stem to the handle 1 where it is connected to the battery 60 cells 20 and 21, which are conveniently mounted in the handle and within the insulated lining 22 therefor.

The inner pole 23 of the cell 20 contacts with the conductor 18 and the inner pole 65 of the cell 21 with the outer casing of the

cell 20. The cells are held in contact by means of the spring 25 which has metallically connected to its outer end the plate 26. The latter contacts with the plate 27 connected to the binding post 28, which latter passes through a sleeve 29, insulating the binding post from the handle casing 1. A second binding post 30 is threaded into the end of the handle casing so that it has metallic connection through the casing and the 75 contact member with the electrode 10.

Any suitable listening device may be employed, but herein I have utilized a pair of head telephone receivers 31 and 32, connected together by a resilient band 33 adapted 80 to hold the receivers in position against the ears of the listener. The two receivers are connected in series by the insulated conductor 34 which connects a terminal on one receiver to a terminal on the other, the remaining terminals being connected, respectively, by the insulated conductors 35 and 36 to the binding posts 28 and 30.

In using the described apparatus the head receivers having been placed in position, the operator holds the device by the handle 1 and places the contact member in contact with the solid or liquid body, the vibrations in which are to be tested. If, for example, this is the bearing of a shaft, the sound heard at the transmitter will result exclusively from the sounds transmitted through the walls of the bearing against which the contact member rests and none of the sounds external thereto and transmitted through the air will in any way affect the microphone or be manifested at the receiver. If the shaft is running evenly and true the sound transmitted will indicate this, but if running unevenly or out of alinement the irregular sound transmitted will at once indicate the fact, and the degree of irregularity in running will also be evident. The microphone being unresponsive wholly to air vibrations, such a test, so far as the transmitting qualities of the instrument are concerned, may be conducted in a noisy workshop and in the midst of the greatest din and noise as readily as in a quiet room. This example is merely illustrative of numerous uses to which the apparatus may be applied. Another example of its application is for the detection of leaks in water or other liquid-conducting pipes. When the pipe is intact and water flowing regularly through it, this fact can readily be determined by contact with the pipe or other solid body associated therewith. When there is a break or other leak in the pipe, however, and there is an abnormal flow of water, the contact between the conductor and the pipe, or any spot in its vicinity, will enable the listener to discover it from the sound in the receiver.

It is to be understood that my invention

has extensive application to purposes widely different from those suggested, and is susceptible of embodiment in a great variety of forms without departing from the spirit 5 of the invention.

Having thus described my invention, what I claim is;

1. In an apparatus of the class described, the combination of a portable completely 10 closed casing for contact with a solid body, a microphone contained in said casing and connected to a suitable receiver, said casing being sufficiently rigid and thick to insulate the microphone from external sounds except those received by contact and a vibration-conducting connection projecting inward from said casing and secured to said microphone substantially in axial line with the vibratory center of said microphone.

2. An apparatus of the class described comprising in combination, an electro-microphone detector connected to a suitable receiver, a metallic contact casing entirely 15 enclosing said detector and of a suitable thickness to insulate the detector from external sounds excepting those received by contact between said casing and a solid body, and vibration-conducting means rigidly connected to said casing and to said microphone, substantially in line with the point 20 of maximum vibration of the latter.

3. A portable sound-detecting device comprising a closed contact casing having thick, rigid, walls for insulating the interior thereof from external sounds except those received by contact between said casing and a solid body, a microphone contained in said casing, and an element constituting a rigid connection between said casing and said 35 microphone for conducting vibration from the former to the latter.

4. A portable sound detecting device comprising a small closed metallic casing consisting of thick walls for insulating the interior of said casing from external sounds, excepting those received by contact between said casing and a solid body, a microphone slightly smaller than said casing contained in the latter and an element rigidly connecting said microphone with a wall of said casing and constituting the sole supporting means for said microphone.

5. A portable sound-detecting device comprising a metallic closed contact casing having thick walls for insulating the interior thereof from external sounds, excepting those received by contact between said casing and a solid body, a microphone contained in said casing comprising a casing 55 having a fixed electrode and a movable electrode, and a rigid connection between said fixed electrode and an inner wall of said contact casing.

6. In an article of the class described, the 60 combination of a portable device compris-

ing a casing having integral therewith a contact wall and containing a battery and a transmitter in electric circuit, said transmitter being secured to the inner face of said contact wall of said casing, a receiver, and wire connections between said device and receiver.

7. In an article of the class described, the combination of a portable casing having a closed chamber at one end, one end wall of which is integral with said casing, while the opposite wall is hermetically sealed thereto, a battery in a second chamber in said casing, a transmitter secured to the first-mentioned wall, a receiver, and means for connecting said receiver, battery and transmitter in electric circuit.

8. In an article of the class described, the combination of a portable casing having a handle at one end and a chambered member 85 at the opposite end, one end wall of which is integral with said casing and provided with an outer contact surface extending beyond all other parts of said casing, a battery in and insulated from said handle, a transmitter suspended in said chambered member, an electric connection between said transmitter and casing, an electric connection between said transmitter and battery insulated from said casing, a receiver, and electric connections 90 between said receiver and casing and said receiver and battery.

9. In an article of the class described, the combination of a portable casing having a handle at one end and a chambered member 100 at the opposite end, one end wall of which is integral with said casing and provided with an outer contact surface extending beyond all other parts of said casing, a battery in and insulated from said handle, a 105 member extending inwardly from one wall of said chamber, a transmitter suspended thereon, an electric connection between said transmitter and casing, an electric connection between said transmitter and battery 110 insulated from said casing, a receiver, and electric connections between said receiver and casing and said receiver and battery.

10. In an article of the class described, the combination of a portable casing having 115 a handle at one end and a hermetically sealed chamber at the opposite end, a battery in and insulated from said handle, a member extending inwardly from one wall of said chamber, a transmitter in said chamber, an electric connection between said transmitter and casing, an electric connection between said transmitter and battery insulated from said casing, a receiver, and electric connections between said receiver 120 and casing and said receiver and battery.

11. In an article of the class described, the combination of a casing having at one end a closed chamber, one end of which is provided with a contact surface extending 130

beyond all other parts of said casing, a transmitter in said chamber, one electrode of which is connected to said casing, a handle for said casing, a battery therein connected to the other electrode and insulated from said casing, a receiver, and wires connecting said receiver, battery and transmitter in circuit.

In testimony whereof, I have signed my name to this specification, in the presence of 10 two subscribing witnesses.
